UNITED STATES PATENT OFFICE.

ROBERT H. KROOS, OF SHEBOYGAN, WISCONSIN.

DRAWER-GUIDE.

1,111,026.

Specification of Letters Patent. Patented Sept. 22, 1914.

Application filed May 24, 1913. Serial No. 769,545.

To all whom it may concern:

Be it known that I, ROBERT H. KROOS, a citizen of the United States, and resident of Sheboygan, in the county of Sheboygan and State of Wisconsin, have invented new and useful Improvements in Drawer-Guides, of which the following is a description, reference being had to the accompanying drawings, which are a part of this specification.

10 This invention relates to improvements in drawer guides.

It is one of the objects of the present invention to provide a drawer guide which will eliminate friction to a considerable extent and prevent binding of the parts.

15 A further object of the invention is to provide a drawer guide which will facilitate the opening and closing of the drawer and which will prevent the tilting of the drawer 20 downwardly when the drawer is withdrawn almost entirely out of its casing.

A further object of the invention is to 25 provide a drawer guide which may be easily applied to ordinary drawers now in common use.

30 A further object of the invention is to provide a drawer guide having anti-friction means which are so constructed as to eliminate the possibility of any of the parts 35 becoming lost or getting out of their proper position.

A further object of the invention is to 35 provide a drawer guide which is of simple construction, is strong and durable and is well adapted for the purpose desired.

With the above and other objects in view, the invention consists of the improved 40 drawer guide and its parts and combinations as set forth in the claims, and all equivalents thereof.

In the accompanying drawing in which the same reference characters indicate the same parts in all of the views: Figure 1 is a front view of a portion of a piece of furniture or 45 casing having the improved drawer guides mounted therein, the drawer being in section; Fig. 2 is an enlarged side view of one of the drawer guides; Fig. 3 is a transverse sectional view thereof on a larger scale; Fig. 50 4 is a view similar to Fig. 1 of a modified form of drawer; and Fig. 5 is a similar view of one side portion of another modified form thereof.

Referring to the drawing the numeral 8 55 indicates a portion of a casing or piece of furniture having a sliding drawer 9 pro-

vided with the improved guides 10. In order to accommodate the improved guides, the lower corner edges of the side portions 11 of the drawer are beveled off inwardly 60 downwardly as indicated by the numeral 12 and the guides 10 which are triangular in form in cross section are mounted in the corner spaces 13 of the casing formed by the beveled edges. The upper angled faces 65 14 of the guides are spaced a slight distance from the beveled edges of the drawer to avoid contact therewith and anti-friction balls 15 carried by the guides and projecting through openings 16 and 16' in the angled faces of the guides are engaged by said beveled drawer edges and centered and spaced between the side faces 17 of the case. The medial openings 16' of the guides are 70 of slotted or elongated form to permit the anti-friction balls to freely roll therein the length of movement the drawer is pulled 75 outwardly and thus prevent the frictional engagement of the balls with the end edge portions of the angled faces forming the 80 slots, while the end openings are of a size to hold the balls in position to support the drawer when the drawer is pulled outwardly. As the ball openings are of less width than the diameter of the balls the 85 balls cannot be displaced or knocked out when the drawer is withdrawn from the casing.

The casings of the guides are formed of strips of metal 17 bent in right-angled form 90 longitudinally of their lengths and the face portions 14 of said casing are secured to the angled lengths by bent over edge portions 18 which overlap the side edges of the angled strip and form a slidable cover connection therewith. The base portions 19 95 of the guide casings are supported on the strip 20 forming part of the ordinary casing or furniture construction and the base portions 19 are provided with projecting 100 apertured ends 21 to receive nails or screws to firmly secure the casings to the strips 20.

In the modified form shown in Fig. 2 the upper side corner edges 22 of the drawer are beveled off in the same manner as the lower edges and the same kind of improved guides 10 are placed in the upper corners to center and space the drawer from the walls of the casing and thereby prevent binding of the parts.

In the form shown in Fig. 5 a flat metal strip 23 mounted on a triangular shaped

strip 24 is substituted for the anti-friction guides to provide a less expensive guide having some of the advantages of the other forms.

5 From the foregoing description it will be seen that the improved drawer guide is well adapted for the purpose desired.

What I claim as my invention is:

1. In combination with a casing having a 10 drawer opening and a slideable drawer therefor having beveled edges, of guide members therefor comprising guide casings of triangular form in cross section and having 15 openings in their upper angled faces adjacent to the beveled drawer edges, some of said openings being of elongated form to permit a rolling movement of balls which project through the openings, and balls mounted within the casings and engaging 20 two sides of the casing and projecting

through the openings and being engaged by the adjacent beveled edges of the drawer.

2. A drawer guide, comprising a strip of right-angled material, a cover strip therefor having angled side edges which slidably 25 engage the side edges of the right-angled strip, said cover also having an elongated opening, and a ball positioned within the space formed by the angled strip and the cover and engaging two side walls of the 30 angled strip and projecting through the cover opening, said cover opening being of less width than the diameter of the ball.

In testimony whereof, I affix my signature, in presence of two witnesses.

ROBERT H. KROOS.

Witnesses:

WILLIAM KIRBER,
O. W. EICKMEYER.
